Des. 185,267
Patented May 26, 1959

185,267

STREET LIGHT LENS

William H. Dorman and Franklin M. Neal, Corning, N.Y., assignors to Corning Glass Works, Corning, N.Y., a corporation of New York

Application March 5, 1958, Serial No. 49,907

Term of patent 14 years

(Cl. D48—16)

Fig. 1 is a front elevational view of a street light lens embodying our new design.

Fig. 2 is a side elevational view thereof.

Figs. 3, 4 and 5 are fragmentary sectional views, on an enlarged scale, taken on lines 3—3, 4—4 and 5—5 respectively.

We claim:

The ornamental design for a street light lens, as shown.
